UNITED STATES PATENT OFFICE.

DANIEL P. CROWLEY, OF TURTLECREEK, PENNSYLVANIA.

METALLIC TIE.

SPECIFICATION forming part of Letters Patent No. 734,306, dated July 21, 1903.

Application filed May 25, 1903. Serial No. 158,630. (No model.)

To all whom it may concern:

Be it known that I, DANIEL P. CROWLEY, a citizen of the United States of America, residing at Turtlecreek, in the county of Allegheny and State of Pennsylvania, have invented certain new and useful Improvements in Metallic Ties, of which the following is a specification, reference being had therein to the accompanying drawings.

- 10 This invention relates to certain new and useful improvements in metallic ties, and has for its object to provide a metallic tie upon which the rails may be secured by the ordinary fastenings now generally used.
- 15 Another object of my invention is to provide a metallic tie which when the same has had its upper face injured or damaged to any extent may be reversed and the under side used, thereby providing the tie which will receive double wear of the ordinary ties now in use.

20 A still further object of my invention is to provide a metallic tie which can be readily formed from sheet metal, said tie being strong and durable and highly efficient when used.

25 Briefly described, my metallic tie comprises a channel-bar which has its ends or sides bent inwardly, these sides being again bent downwardly, the edges of said sides being bent at 30 right angles on a line parallel to the base of the channel-bar, these outwardly-extending flanges being riveted thereto. Upon the upper face of the tie I secure by ordinary means a base-plate to receive the base of the rail.

35 Within said tie I provide novel means for spacing and bracing the top and base of the tie and means whereby the ordinary spike may be secured to the tie.

40 In describing the invention in detail reference is had to the accompanying drawings, forming a part of this specification, and wherein like numerals of reference indicate like parts throughout the several views, in which—

45 Figure 1 is a top plan view of my improved tie. Fig. 2 is a detail perspective view of one of the ends of said tie. Fig. 3 is a longitudinal sectional view of one of the ends, showing the rail in place upon the same. Fig. 4 is a 50 vertical sectional view of one of the braces carrying the spike-holding means. Fig. 5 is a perspective view of one of the truss bars or

clamps I may employ to brace said tie. Fig. 6 is a bottom plan view of the end of my improved tie.

To put my invention into practice, I provide a channel-bar 1, the sides of said channel-bar being of greater length than the width of said channel, and in the construction of my improved tie I bend the sides 2 and 3 at 60 right angles to each other forming the top of the tie, as indicated at 45. I again bend said ties downwardly on a line almost parallel to the sides 2 and 3, as indicated at 6 and 7, and the lower edges of these downwardly-bent 65 portions 6 and 7 I again bend or form at right angles to each other, as indicated at 8 and 9, these outwardly-extending flanges 8 and 9 being on a plane to the base 10 of the channel-bar. I rigidly secure said flanges on the 70 base by means of the rivets 11. To the upper faces or top of said tie I secure the base-plate or chair 12, which is riveted or otherwise secured, as indicated at 14 and 15, said chair or base-plate having formed on its outer 75 end a raised portion 16, forming a shoulder 17, against which the base of the rail abuts.

In order to brace the top of my improved tie, I provide a tubular support 18, which carries another tubular casing 19, in which 80 is driven the spike 20. The tubular brace 18 is adapted to be the length of the distance between the top of the tie and the base 10, whereby the faces 4 and 5 will rest upon the shoulder 21 of the tubular support 18, and 85 the annular shoulder 22 will rest against the base 10 of the channel-bar. In the top faces 4 and 5 of the metallic tie and the base 10 are formed apertures 23 and 24, said apertures registering in vertical alinement with each 90 other and with apertures 25 and 26, formed in the base-plate. The tubular casing 19 is made of greater length than the tubular support 18, thus providing the projecting ends 26 and 27, and through the apertures 24 and 95 25 I secure the projecting end 26 of the tubular casing 19, and through the aperture 23 of the base 10 I secure the projecting end 26 of the tubular casing 19. In the tubular casing 19 I secure by any desired means, preferably friction, the block of wood 28, into which is driven the spike 20, the insertion of which compresses the wood 28, thereby rigidly and securely holding the spike.

It will be seen in Figs. 1 and 2 of the drawings that I have shown the apertures 26 diametrically opposite each other, one aperture being formed in the top surface 4, while the other of said apertures is formed in the top surface 5, the apertures in the base 10 corresponding therewith.

In Fig. 5 of the drawings I have illustrated a truss-bar which may be employed for bracing my improved metallic tie, said truss-bar consisting of the plates 29 and 30, these plates being held against the ends of the tie by means of the truss-bar 31, which is adapted to pass through plate 30 and have a nut or tap secured upon its end. This construction, as just described, is only used where it is found necessary to strengthen my improved tie.

Another feature of my invention to which I wish to call particular attention is illustrated in Figs. 1 and 6 of the drawings. When the top surfaces 4 and 5 have been damaged or otherwise injured by a derailed train, the same may be reversed and the base of said tie used to secure the rails in proper position, the apertures 23 being provided for the admittance of the spike, which is driven into the wooden block carried in the tubular casing 19. The base-plates 12 may be easily and quickly secured to this surface of the tie as it may be desired.

While I have herein shown and described my invention, it is obvious that I do not care to limit myself to the exact construction, as various changes may be made in the details of construction without departing from the general spirit of my invention.

Having fully described my invention, what I claim as new, and desire to secure by Letters Patent, is—

1. A metallic tie comprising a channel-bar, said channel-bar having its sides bent at right angles, said sides being bent downwardly, said bent-down portions having their edges bent at right angles on a line parallel to the base of the channel-bar, and secured thereto, a base-plate or chair secured to the top of the channel-bar, means for bracing the top and base of the tie, means carried within said braces whereby a spike may be driven there-

in for holding the rail in position upon the tie, substantially as described.

2. A metallic tie comprising a channel, said channel-bar having its sides bent at right angles, said sides bent downwardly, said bent-down portions having their edges bent at right angles on a line parallel to the base of the channel-bar and secured thereto, a chair secured upon the upper face of the tie, a tubular support or brace carried within the tie, a tubular casing supported in said brace, apertures formed in the top and base of the tie, apertures formed in the base-plate or chair carried by the tie, said apertures registering in vertical alinement with the apertures formed in the tie, said tubular casing having its ends secured in the apertures formed in the base-plate and the tie, means carried within said tubular casing for rigidly securing a spike therein, substantially as described.

3. A metallic tie comprising a channel-bar, said channel-bar having its sides bent at right angles, said sides bent downwardly, said bent-down portions having their edges bent at right angles on a line parallel to the base of the channel-bar and secured thereto, a chair secured upon the upper face of the tie, a tubular support or brace carried within the tie, a tubular casing supported in said brace, apertures formed in the top and base of the tie, apertures formed in the base-plate or chair carried by the tie, said apertures registering in vertical alinement with the apertures formed in the tie, said tubular casing having its ends secured in the apertures formed in the base-plate and the tie, means carried within said tubular casing for rigidly securing a spike therein, a truss-bar having plates secured to its outer ends, said truss-bar passing through the body portion of the tie and rigidly supporting the ends and body portion of said tie, substantially as described.

In testimony whereof I affix my signature in the presence of two witnesses.

DANIEL P. CROWLEY.
